2 Claims. (Cl. 339—223)

This invention relates to electrical plug and socket connectors, and more particularly to an improvement in a resilient detent for releasably securing the parts together.

Connectors of this nature are particularly suitable and adaptable for connecting high tension conductor cables to automotive distributor heads or the like, the sockets being disposed in insulating sleeves fixed in the heads.

It is desirable for the plugs which are attached to the ends to the electrical cables, to be firmly and securely, but releasably, retained in the sockets. In known connectors of this type the plug usually has several detent elements which have the same axial location along the plug and thus operates simultaneously as a unit when the plug is engaged or disengaged from the socket. The forces required to depress the detents thus reach their highest values simultaneously during the plug withdrawal and can become so high as to render the plug difficult to remove from the socket. An object of the invention is the provision of a plug which can easily be removed from the socket and is of simple construction while being rugged in use and foolproof in operation.

According to the invention a recess in the socket and the detents of the plug are so arranged that the forces required to depress the detents do not reach their highest values simultaneously.

Other objects and attainments of the present invention will become apparent to those skilled in the art upon a reading of the following detailed description when taken in conjunction with the drawings in which is described an embodiment of the invention; it is to be understood, however, that the embodiment is not intended to be exhaustive nor limiting of the invention but is given for purposes of illustration in order that others skilled in the art may fully understand the invention and the principles thereof and the manner of applying it in practical use so that they may modify it in various forms, each as may be best suited to the conditions of a particular use.

The preferred embodiment will now be described by way of example with reference to the accompanying drawing in which:

FIGURE 1 is a perspective view of the connector plug member;

FIGURE 2 is a top plan view of the plug member;

FIGURE 3 is an end view of the plug as it is shown in FIGURE 2;

FIGURE 4 is a side elevational view of the connector plug member disposed in an insulating sleeve, the socket member and the sleeve being illustrated in longitudinal section.

In a preferred embodiment of the invention, the detents are formed as arcuate peripheral ribs on the plug body, the cooperating recess being a groove in the socket extending parallel to the ribs.

The plug is constituted by a cylindrical metal ferrule 2 which is received in the bore 4 of a socket 6, and receives the end of an insulated cable 8.

The plug is preferably a cylindrical ferrule substantially the length of which is arranged to surround the cable to which it is attached so that the ferrule is not deformed in the event the cable is pulled in the transverse direction of the ferrule.

2

A triangular spear 10 cut from the wall of the ferrule 2 has been bent at a right angle inwardly of the ferrule 2 piercing the insulation 12 of the cable 8 and extending into the core 14 of the cable to provide a permanent electrical connection between ferrule 2 and core 14. Further spears 36 or the like have also been cut from the wall of the ferrule 2 and have also been bent inwardly of the said ferrule, and protrude or extend into the insulation 12 to prevent relative axial movement between the cable 8 and ferrule 2. As best seen in FIGURE 2 the ferrule 2 has a recess 16 from the walls 18 and 20 of which extend two opposed tongues 22 and 24. The tongue 22 has been bent to provide an arcuate detent rib 26 which is resiliently depressable and extends in a circumferential direction of the ferrule 2 and is wedge shaped as seen in cross-section. A similar detent rib 28 on the tongue 24 is displaced from the rib 26 in the axial direction of the ferrule 2. The detent ribs 26 and 28 are both received in a circumferential groove 30 of semi-circular cross-sectional shape on the internal surface of the socket member 6 as can be seen in FIGURE 4. The groove 30 has been formed by pressing the wall of the socket 6 to provide a rib 32 complementary to the groove 30, rib 32 to be received in an inner circumferential groove 34 in an insulating sleeve forming part 38, for example, of a distributor head, to prevent relative axial movement between the member 6 and the sleeve 38. The sleeve 38 has a bell mouth 40 to act as a guide for inserting the ferrule 2 into the bore 4. To remove the ferrule 2 from the bore 4, the cable 8 is pulled in the direction indicated by the arrow in FIGURE 4. The detent rib 28 is cammed by the right hand portion of the wall of the groove 30 and is depressed so that it can pass along the bore 4 in the direction of the arrow.

When the rib 28 has been fully depressed, the detent rib 26 reaches a wall portion adjacent the aforesaid wall portion and is in turn depressed to pass along the bore 4 in the same manner as detent rib 28. The forces required to depress the two ribs thus reach their maximum value at different periods during withdrawal of the ferrule 2. The wedge shaped construction of the detent ribs 26 and 28 facilitates the insertion of the ferrule 2 into the bore 4.

Since the ferrule 2 surrounds the end of cable 8 throughout the length of the ferrule, the ferrule is not readily deformed if the cable is pulled in the transverse direction of the ferrule. Since the tongues 22, 24 and the detent ribs 26 and 28 and the spears 10 and 36 are all integral with the ferrule 2, a ferrule blank can readily be stamped from a sheet of metal, e.g., brass, and subsequently rolled to form the ferrule in a rapid and inexpensive manner.

Since the right hand end, see FIGURE 4, of the detent rib 28 abuts one wall of the groove 30, and the left hand end of the detent rib 26 abuts the opposite wall of the groove 30 relative axial movement between the ferrule 2 and socket 6 is prevented. As can be noted the plug can easily be removed from the socket and is of simple design, yet rugged and foolproof in actual operation.

While there have been illustrated and described fundamental novel features of the invention, it will be understood that various omissions and substitutions and changes in the form and details of the device illustrated and its operation may be made by those skilled in the art without departing from the spirit of the invention. It is the intention, therefore, to be limited only as indicated by the scope of the following claims.

We claim:

1. For use to connect electrically with a socket having an internal annular recess, a metallic plug having a plurality of detent projections or resilient cooperation with

said recess to retain the plug in the socket, said projections being offset from one another along the insertion axis of the plug for sequential depression thereof upon insertion and withdrawal of the plug into and from the socket, the maximum axial spacing of the projections being less than the width of the recess in which it is intended to engage, each projection defining a tapered surface inclined towards the longitudinal axis of the plug in the insertion direction thereof which merges into another tapered surface extending in an opposite direction with respect to said first-mentioned tapered surface, the inclined surface of the projection nearest the insertion end of the plug adapted to wedgingly engage an interior wall portion of the socket adjacent said recess, the other tapered surface of the other projection adapted to engage 15 said recess.

2. An electrical connector comprising a socket having an internal annular recess, a plug receivable in said socket and including a ferrule for crimping about an electrical lead wire and a pair of opposed tongues disposed for 20 independent resilient depression, a detent rib on each of said tongues defining a pair of detent ribs cooperable with said recess to retain the plug in the socket, one rib being offset from another along the insertion axis of the plug for sequential depression thereof upon withdrawal 25 of the plug from the socket, the axial spacing of said ribs being less than the width of said recess, the detent rib nearest the insertion end of the plug having a tapered sur-

5
face inclined towards the longitudinal axis of the plug in the insertion direction thereof for wedging engagement with the interior surface of the socket, and the other detent rib having a surface facing oppositely to the insertion direction for resilient engagement with the recess to drive the inclined surface into tight wedging engagement with the interior surface of the socket.
